CLAIM

The ornamental design for a display screen or portion thereof with graphical user interface for media playback control, as shown and described.

DESCRIPTION

FIG. 1 is a front view of a display screen or portion thereof with graphical user interface for media playback control according to a first embodiment of the invention; and, FIG. 2 is a front view of a display screen or portion thereof with graphical user interface for media playback control according to a second embodiment of the invention. The broken line showing of text and graphic elements forms no part of the claimed design.
